HANS RUDOLPH FRIEDRICH KOCK AND KARL ALFRED RUDOLF QUITT, OF LUBECK,
GERMANY

BOILER AND EVAPORATOR

Application filed June 4, 1926, Serial No. 282,802, and in Austria June 27, 1927.

Since steam-boiling has been introduced in breweries, distilleries, sugar-factories and similar industries, numerous constructions of boiling vessels have been applied the effect of which is, as regards economy, greatly superior to the cooking on fire. The fuel-consumption has been considerably reduced by the more economical steam-boiling.

As, however, the temperatures of the walls of the heating apparatus during fire-cooking and steam-cooking are different, the cooking processes are also different. Specially in breweries it has been found that beer brewed by fire-boiling is better, under otherwise similar conditions, than beer produced by steam-boiling. This is due to the fact, that owing to the high wall-temperatures during fire-boiling superheated steam-bubbles are produced in the liquid to be boiled, which have a favourable influence on the product. This favourable influence cannot be obtained in a similar manner by steam-boiling.

The invention consists in arranging a rising pipe communicating with the lower portion of the boiling vessel and containing a heating device, the upper end of said rising pipe projecting into the upper portion of the inner space of the boiling vessel.

Several embodiments of the invention are illustrated, by way of example, in the accompanying drawings, in which:—

Fig. 1 shows in section a combined mash and wort-tun with a new boiling and evaporating device.

Fig. 2 shows in section another form of construction of the mash and wort-tun.

Fig. 3 shows in top plan view a distributor for the boiling and evaporating device.

Fig. 4 is a similar view as Fig. 3 showing a distributor of other construction.

Fig. 5 shows a constructional detail of the heating device for the boiling and evaporating device.

Figs. 6 and 7 show each in section partly in elevation, a portion of a mash and wort-tun of modified constructions.

The boiling and evaporating device shown in Fig. 1 consists of a heating body comprising a centrally arranged steam supply tube 1 branching into two downwardly directed

heating tubes 2, united at the lower end to form a horizontal tubular heating ring 3. To the lowest point of this tubular heating ring 3 an upwardly directed outflow tube 4 for water of condensation is connected. The tube 1 is connected by a flexible metal tube 7 to a steam valve 5 and the tube 4 by a flexible metal tube 8 to a valve 6 for water of condensation.

A conical open ended casing or rising pipe 9 encloses the heating tubes 1, 2, 3 and it is composed of two parts, hingedly connected the one with the other by a hinge 10.

The two parts of the rising pipe are secured in the closed position by catches or the like. On the central steam supply tube 1 a flange 11 is arranged which serves as support for a distributor 12.

This distributor consists of a tubular central part, the lower end of which projects a short distance into the upper end of the rising pipe 9 so that, when this rising pipe is open, the distributor remains in its position. The distributor is mounted on a double ball-bearing and has any desired number of arms 13 which have either downwardly opening outflows 14 as shown in Fig. 3 or tangential outflows 15 as shown in Fig. 4.

The heating tube 1 is mounted on a transverse bar 16 carried by screw spindles 17 and adapted to be shifted in vertical directions by means of a hand-wheel 19 through the intermediary of a worm driving gear 20 and a horizontal spindle 18.

On the bottom plate of the copper or tun 24, which is covered by a hood 25, a supply pipe 21 is fixed, which has a lower conical portion and an upper cylindrical portion, the latter projecting into the space enclosed by the rising pipe 9.

In the modified form of boiler and evaporator with constant evaporating surface as shown in Fig. 2, the stationary portion of the rising pipe 9 and the hinge bolt 10 are connected with the tun 24 by holders 22 and 23, and the discharge pipe 4 for the water of condensation projects through the bottom plate of the tun.

The branch tubes 2 of the heating device are connected to the ring-shaped tube 3 by a

fitting 30 (Fig. 5), in which a partition 31 for the steam from tube 2 and a partition 32 for the water of condensation are arranged. The water of condensation flows out through an outlet tube 33. Owing to this arrangement the heating steam preserves its original velocity, while the water of condensation continues to flow through the closed ring 3 so that at all points of the wall a uniform temperature is obtained. The water of condensation is further drawn along, owing to the great velocity of the heating steam, and deflected by the partition 32 to be discharged through the outlet tube 33. The flow of heating steam continues to circulate between the partitions 31 and 32, and it is sucked on injector-like by the heating steam injected from tube 2 along the wall 31.

When the boiling or heating device shown in Fig. 1 is operated, its position in vertical direction is adjusted according to the actual level of the mesh or wort in the tun by means of the screw spindle 17 turned by the rotation of the hand wheel 19. The steam valve 5 and valve 6 for the water of condensation are open so that the steam bubbles, produced on the exterior surface of the heating bodies 1, 2 and 3, are distributed through the liquid in the rising pipe 9 and form, with the liquid, a specifically light mixture which is forced upward into the distributor 12 by the over-pressure in the liquid in the tun. A rapid circulation of the liquid to be boiled is thus produced and also a rapid transmission of heat.

When the mixture is flowing out of the distributor-space, the steam is separated and the liquid drops back onto the evaporating surfaces so that boiling over or rising of froth are prevented.

The distributor 12 shown in Fig. 4 having tangential outflows 15 is rotated, together with the rising pipe 9, around its central axis by the recoil at the outflowing of the liquid.

When the distributor 12 is in an elevated position an injector-like sucking in of the liquid from the tube 21 is obtained by the rapid upward flowing of the liquid in the rising pipe 9 so that also the lower portions of the liquid are agitated and participate in the boiling and in the evaporation. The liquid circulates constantly through the tube 21 and the rising pipe 9.

The operation of the apparatus shown in Fig. 2 is similar.

As regards brewery technics a considerable progress is obtained with the new apparatus for the reason that the mixture of steam and liquid, which is lighter per se, flows at considerable speed along the heating surfaces heated in counter-current, and is superheated so that the valuable roasting products are formed and the disintegration of the extract constituents is effected which

are not easily soluble. This could hitherto be obtained under similar conditions only by the uneconomical boiling with fire.

An essential advantage of the new apparatus is that it can be easily built in any existing boiling vessel without alteration of the same.

The rising pipe, composed of two hingedly connected parts, facilitates cleaning, this being a fundamental condition for a brewery.

A further advantage is the good mixing of the liquid due to the high speed in the rising pipe, whereby a good separating of the fermented wort is ensured.

The boiling and heating devices, shown in Figs. 6 and 7 consists each of a closed rising pipe 36 connected by a tube 37 to the bottom part of the brewer's copper 24, said rising pipe 36 being arranged on the outer side and parallel to the tun or copper, usually in vertical position and connected by an upper outflow tube 38 with the top end of the vessel 24.

In the rising tube 36 a heating body 39 is arranged, concentrically mounted in the rising tube by means of guide ribs 40. A steam supply tube 41 is arranged in the lower portion of the rising pipe 36. At the lowest point of the heating device a discharge tube 42 for the water of condensation is arranged.

In the heating tube 39 closed at both ends a tube 43 open at both ends is concentrically arranged and securely held by fixation ribs 44.

On the end of the steam-supply-pipe 31 a nozzle 45 is mounted which projects injector-like into the tube 43 so that the steam ascends in the tube 43 up to the highest point and descends along the wall of the tube. The steam circulates, owing to the injector action of the nozzle 45, not only in the tube 43 but also in the annular space between the tube 43 and the tube 39. A high heat transmission, a uniform temperature of the entire heating surface and flowing off of the water of condensation are thus ensured.

The form of construction shown in Fig. 7 differs from that shown in Fig. 6 in that the upper end of the discharge-tube 38 is not directly connected to the vessel 24 but by means of an inflow tube 38a which is rigidly connected to the vessel 24 and adapted to be connected to the end of tube 38 by a screw-connection. The lower end of the rising tube 36 is connected with the connecting tube 37 by a fitting 36a.

This fitting 36a, or the lower edge of the heating tube 39, is lower than the bottom-plate of the vessel 24 so that, even when the vessel 24 does not contain much liquid, the liquid column in the rising pipe 36 is comparatively high, whereby the rising of the liquid to the outflow tube 38 is ensured.

In the fitting 36a a tubular inlet and out-

let are arranged. The outlet tube is closed by a cock 48 which establishes the connection with the pump 49 by means of which the liquid may be pumped from out of the vessel so that the rising pipe may be emptied.

The arrangements shown in Figs. 6 and 7 are operated by opening the outflow valves 35, whereupon the liquid contained in the vessel 24 rises, according to the law of the 10 communicating tubes, in the tubes 36 to the same height as in the vessels.

By the evaporizing a specifically lighter mixture is produced in the tubes 43 which is returned into the vessels by the pressure in 15 said vessels through the curved outflow pipes 38.

We claim:—

1. A boiling and evaporating device for 20 boiling vessels specially for brewer's coppers, comprising in combination with the vessel proper, a rising pipe communicating with the lower portion of said vessel and a heating element in and closed against said rising pipe, means for admitting steam to the heating element, the upper end of said rising pipe communicating with the upper portion of said boiling vessel, and means for conveying the water of condensation of the steam in the heating element away from said 25 element.

2. A boiling and evaporating device for 30 boiling vessels specially for brewer's coppers, comprising in combination with the vessel proper, a rising pipe communicating with the lower portion of said vessel, a heating device in said rising pipe the upper end of said rising pipe communicating with the upper portion of said boiling vessel, and a distributor having several arms on said heating 35 device.

3. A boiling and evaporating device for 40 boiling vessels specially for brewer's coppers, comprising in combination with the vessel proper, a rising pipe communicating with the lower portion of said vessel, a heating device in said rising pipe, the upper end of said rising pipe communicating with the upper portion of said boiling vessel, and a distributor having several arms on said heating 45 device each arm having a downwardly directed mouth.

4. A boiling and evaporating device for 50 boiling vessels specially for brewer's coppers, comprising in combination with the vessel proper, a rising pipe communicating with the lower portion of said vessel, a heating device in said rising pipe the upper end of said rising pipe communicating with the upper portion of said boiling vessel, and a distributor 55 having several arms rotatably mounted on said heating device each arm having a tangentially directed mouth.

5. A boiling and evaporating device for 60 boiling vessels specially for brewer's coppers, comprising in combination with the vessel

proper, a rising pipe communicating with the lower portion of said vessel and a heating device in said rising pipe the upper end of said rising pipe communicating with the upper portion of said boiling vessel, said 70 heating device consisting of a tube branching at the lower end into two tubes, and a ring-shaped tube connecting the lower ends of said branch tubes.

6. A boiling and evaporating device for 75 boiling vessels specially for brewer's coppers, comprising in combination with the vessel proper, a rising pipe communicating with the lower portion of said vessel, and a heating device in said rising pipe, the upper end of said rising pipe communicating with the upper portion of said boiling vessel, said heating device consisting of a tube branching at the lower end into two tubes, a ring-shaped tube connecting the lower ends of 80 said branch tubes, a fitting connecting the lower end of each branch tube with said ring-shaped tube, a tubular outflow in the lower portion of said fitting, a partition in said fitting extending under the open lower end of said branch tube, and a partition in the lower portion of said fitting extending over said outflow tube.

7. A boiling and evaporating device as 85 specified in claim 6 in which a free space is arranged between said two partitions of said fitting through which the heating steam in said ring-shaped tube is sucked ejector-like.

8. A boiling and evaporating device for 90 boiling vessels specially for brewer's coppers, comprising in combination with the vessel proper, a rising pipe communicating with the lower portion of said vessel, a heating device in said rising pipe, the upper end of said rising pipe communicating with the upper portion of said boiling vessel, a distributor having several arms on said heating 95 device, and means for adjusting said heating device and said distributor in vertical directions in said vessel.

9. A boiling and evaporating device for 100 boiling vessels specially for brewer's coppers, comprising in combination with the vessel proper, a rising pipe communicating with the lower portion of said vessel, a heating device in said rising pipe, the upper end of said rising pipe communicating with the upper portion of said boiling vessel, a distributor having several arms on said heating 105 device, and means for adjusting said heating device and said distributor in vertical directions in said vessel, comprising a transverse bar to which said heating device and distributor are suspended, vertical threaded spindles carrying said horizontal bar, a hand wheel, a worm gear, and a horizontal spindle for lowering or raising said vertical spindle.

10. A boiling and evaporating device for 110 boiling vessels specially for brewer's coppers,

comprising in combination with the vessel proper, a rising pipe communicating with the lower portion of said vessel, a heating device in said rising pipe, the upper end of said rising pipe communicating with the upper portion of said boiling vessel, a distributor having several arms on said heating device, and a supply pipe for hot steam centrically extending through said distributor and communicating with said heating device.

11. A boiling and evaporating device for boiling vessels specially for brewer's coppers, comprising in combination with the vessel proper, a rising pipe communicating with the lower portion of said vessel, a heating device in said rising pipe, the upper end of said rising pipe communicating with the upper portion of said boiling vessel, a distributor having several arms on said heating device, and a supply tube conical at the lower end mounted on the bottom plate of said vessel and extending into said rising pipe.

12. A boiling and evaporating device for boiling vessels specially for brewer's coppers, comprising in combination with the vessel proper, a rising pipe communicating with the lower portion of said vessel and composed of two parts, a hinge connecting said two parts of said rising pipe, and a heating device in said rising pipe, the upper end of said rising pipe communicating with the upper portion of said boiling vessel.

13. A boiling and evaporating device for boiling vessels specially for brewer's coppers, comprising in combination a boiling vessel, a rising pipe on the outer side of and parallel to said vessel, a connecting pipe connecting the lower end of said rising pipe with the lower portion of said vessel, a valve for closing said connecting tube, a curved connecting tube connecting the upper end of said rising pipe with the top portion of said vessel, and a heating device in said rising pipe.

14. A boiling and evaporating device for boiling vessels specially for brewer's coppers, comprising in combination a boiling vessel, a rising pipe on the outer side of and parallel to said vessel, a connecting pipe connecting the lower end of said rising pipe with the lower portion of said vessel, a valve for closing said connecting pipe, a curved connecting tube connecting the upper end of said rising pipe with the top portion of said vessel, and a heating device in said rising pipe consisting of two concentrical tubes communicating the one with the other and of a steam supply nozzle projecting into the inner one of said communicating tubes.

15. A boiling and evaporating device for boiling vessels specially for brewer's coppers, comprising in combination a boiling vessel, a rising pipe on the outer side of and parallel to said vessel, a connecting pipe con-

necting the lower end of said rising pipe with the lower portion of said vessel, a valve for closing said connecting pipe, a curved connecting tube connecting the upper end of said rising pipe with the top portion of said vessel, a heating device in said rising pipe, a removable intermediate element connecting said rising pipe to said lower connecting pipe, and an intermediate element connecting said upper curved connecting tube to said vessel.

16. A boiling and evaporating device for boiling vessels specially for brewer's coppers, comprising in combination a boiling vessel, a rising pipe on the outer side of and parallel to said vessel extending a certain distance below the bottom plate of said vessel so that a higher liquid column is formed in said rising pipe than in said boiling vessel.

In testimony whereof we affix our signatures.
